UNITED STATES PATENT OFFICE.

HERBERT HENRY JOHNSON, OF FORBES, AND EDWARD MOIN, OF SYDNEY, NEW SOUTH WALES, AUSTRALIA.

APPARATUS FOR LIGHTING AND EXTINGUISHING GAS-LAMPS.

No. 902,411.

Specification of Letters Patent.

Patented Oct. 27, 1908.

Application filed May 15, 1907. Serial No. 373,839.

To all whom it may concern:

Be it known that we, HERBERT HENRY JOHNSON and EDWARD MOIN, subjects of the King of Great Britain, residing at Lachlan street, Forbes, in the State of New South Wales, Australia, and at 737 George street, Sydney, in said State, respectively, have invented certain new and useful Improvements in Apparatus for Lighting and Extinguishing 10 Gas-Lamps, of which the following is a specification.

This invention relates to improved apparatus for lighting and extinguishing gas lamps provided with a pilot or automatic igniter, by varying the pressure in the main from the regulator at the gasworks or other central station, and has been designed with the view to providing such an apparatus which will operate reliably between a range 20 of any reasonable maximum pressure and a predetermined minimum pressure.

The apparatus is comparatively inexpensive to construct and the employment of levers, springs and like mechanical parts is dispensed with.

Our invention consists essentially of two gasometers or bells provided with suitable liquid seals and contained in a chamber or chambers. One of said bells has a larger 30 effective cross-sectional area than the other which has within it a hood or cover and a seal therefor. The smaller bell is weighted to slightly resist the ordinary or normal pressure in the main while the larger one is 35 weighted so that it will descend further into its seal whenever the pressure falls below the minimum determined upon. But in order that our invention may be clearly comprehended we will refer to the accompanying 40 drawings in which:—

Figure 1 is a perspective view of the apparatus showing a pipe leading to a burner, and a pilot light. Fig. 2 is a central sectional elevation showing the position of the bells at 45 the unlighted position. Fig. 3 is a similar view showing the position the smaller bell takes when the pressure is raised above the normal, while, Fig. 4 is a similar view showing the position of the bells when the gas 50 lamp is burning.

The same numerals refer to the same or corresponding parts.

5 is the smaller bell contained in the chamber 6 having the mercury or other seal 7.

8 is the inlet pipe from the main, and 9 a 55 hood or cover which lies over the outlet pipe 10 which is surrounded by a seal 11.

12 represents a tray or receptacle for shot or other weights. From the outlet 10 the gas passes into the second bell 13 in the 60 chamber 14 by the inlet 15 said bell being also provided with a liquid seal 16.

17 is a receptacle for weights and 18 the outlet pipe to the burner 19.

20 and 21 are suitable guide rods while 22 65 and 23 are brackets on the bells 5 and 13 respectively carrying suitable friction rollers 25 which travel on the fixed guide rod 24. The bracket 22 rests on the bracket 23.

The operation of the apparatus is as follows:—The bell 5 is weighted sufficiently to resist being lifted by the normal pressure in the main which for illustrative purposes we will say is 25 units. The pressure in the main is then raised to say 26 or more units 70 thereby lifting said bell 5 and consequently raising the hood 9 out of the seal 11 (as shown in Fig. 3) allowing the gas to enter the outlet pipe 10 leading to the weighted second bell 13 which it lifts (Fig. 4) on overcoming 75 the weight, thus permitting the gas to pass to the burner where it is ignited by the pilot which is always alight. The pressure in the main is then lowered to the normal (25 units) but the bell 13 having a larger capacity and 80 assisting through its bracket 23 supports the bracket 22 to hold up the bell 5.

The bell 13 is weighted to resist closing lower in its seal until the pressure is reduced below the minimum, which for example is 15 90 units. To extinguish the light the pressure in the main is reduced below 15 units thereby enabling the bell 13 to descend further in its seal and allowing the bell 5 to do likewise. To relight the lamp it will be necessary to 95 increase the pressure in the main to over the normal that is according to our illustration over 25 units.

It will be understood that the bells are never raised out of their seals and that the 100 hood is only lifted from its seal to permit the passage of gas.

It is obvious that the bells could operate in one large chamber provided they were suitably sealed, and that the details of the apparatus could be modified without departing 105 from the leading features.

Having thus described our invention what

we claim as new and desire to secure by Letters Patent is:—

1. In a gas regulator, the combination of a pair of communicating gasometers, one of which is adapted to receive gas from a gas main and the other gasometer being adapted for attachment to an outlet pipe, a gas controlling device operable by the receiving gasometer for regulating the flow of gas therefrom to the other gasometer, and a device operable by the gasometer to be connected to the outlet pipe and adapted to co-operate with the gasometer which operates the gas controlling device for retaining the latter in open position during normal pressure in the main.
2. In an apparatus for lighting and extinguishing gas lamps, the combination of a pair of communicating gasometers of different cross sectional area, a guide rod, brackets carried by said gasometers, friction rollers on said brackets and adapted to travel on said guide rod, the said bracket carried by the larger gasometer being adapted to engage the bracket of the smaller gasometer and thereby maintain both of the gasometers in their raised position after the maximum pressure has been reduced to normal pressure in the main.
3. An apparatus for lighting and extinguishing gas lamps comprising a pair of communicating gasometers of different cross sectional area provided with seals, the smaller of which gasometers is provided with an internal hood and weighted to resist the normal pressure of the gas in the main, and the larger of which is weighted so as to descend into its seal at a predetermined pressure in the main and means operable by the larger gasometer for controlling the movement of the smaller gasometer.
4. In an apparatus for lighting and extinguishing gas lamps, the combination of a chamber, a pair of communicating gasometers of different cross sectional area, an inlet and an outlet for said chamber, seals for said gasometers, a coacting hood and seal mounted within the smaller gasometer for controlling the admission of gas, both of said gasometers being weighted, the smaller one to resist the normal pressure and the larger one

to descend into the seal at a predetermined minimum pressure and means operable by the larger gasometer for retaining the said seal in open position during normal pressure in the main.

5. In an apparatus for lighting and extinguishing gas lamps, the combination of a chamber, a pair of communicating gasometers of different cross sectional area, means for guiding the gasometers, an inlet and an outlet for said chamber, seals for said gasometers, a coacting hood and seal mounted within the smaller gasometer for controlling the admission of gas, both of said gasometers being weighted, the smaller one to resist the normal pressure and the larger one to descend into the seal at a predetermined minimum pressure, and means operable by the larger gasometer for retaining the smaller gasometer in elevated position during normal pressure in the main.

6. In an apparatus for lighting and extinguishing gas lamps, the combination of a chamber, a pair of communicating gasometers of different cross sectional area, an inlet and an outlet for said chamber, seals for said gasometers, a coacting hood and seal mounted within the smaller gasometer for controlling the admission of gas, both of said gasometers being weighted, the smaller one to resist the normal pressure and the larger one to descend into the seal at a predetermined minimum pressure, a guide rod, brackets carried by said gasometers, friction rollers mounted on the brackets and adapted to travel on said guide rod, said bracket carried by the larger gasometer being adapted to engage the bracket of the smaller gasometer and thereby maintain both of the gasometers in their raised position after the maximum pressure has been reduced to normal pressure in the main.

In testimony whereof we have hereunto set our hands in presence of two subscribing witnesses.

HERBERT HENRY JOHNSON.
EDWARD MOIN.
